ELECTRON TUBE STRUCTURE

Joseph W. Skehan, Stamford, Conn., assignor to
Machlett Laboratories, Incorporated, Spring-
dale, Conn., a corporation of Connecticut

Application November 1, 1951, Serial No. 254,330

1 Claim. (Cl. 313—285)

1

This invention relates to a novel electron tube structure. More particularly this invention relates to an electrode support structure having a terminal in the wall of the vacuum envelope. It also concerns a grid construction of great simplicity.

For years a serious problem in the electronics industry has been the alignment and positioning of elements within electron tubes. The problem involves mechanically supporting the weight of the various electrodes and electrically connecting each electrode to a terminal member having a contact surface outside the tube envelope. Frequently the mechanical support structure has been complicated, and positioning and alignment of a particular tube element has involved adjustment of a great many members in this support structure. Even after difficult and time consuming alignment procedures, the alignment and positioning of the electrodes within the tube have often been far from accurate.

My invention provides a solution to the positioning and alignment problem. It employs an extremely simple support member, namely an elongated member of substantially large cross section, to support the weight of the tube element involved. One end of this elongated support member is affixed to the electrode. The other end of the support member is terminated in a portion of enlarged diameter. The enlarged portion is received within a cup-like member which is sealed to the vacuum envelope. The fit between the enlarged portion and the cup is advantageously snug, the cup-like member acting like a socket. The advantage of this structure lies in the mechanical support provided for the tube element even during adjustment in its position. Using such a structure, the element may be moved in at least one direction and thus positioned as desired before permanently affixing the enlarged portion within the cup. Once in position, the exact location of the supported element may be permanently preserved by spot welding the enlarged portion of the elongated member to the cup. Such an operation is easily and quickly accomplished without moving the tube in any way. Thereafter, particularly if the intended use of the tube calls for rough handling, an even stronger bond may be achieved by the additional use of brazing solder.

Even greater flexibility for positioning and alignment may be acquired by rounding the enlarged portion to an ellipsoidal shape. With such a structure the ellipsoidal portion acts as

2

a ball and the cup-like member acts like a socket, the two together forming a type of ball and socket joint. The ellipsoidal portion is therefore usually made almost spherical for best results. Using such a structure, the element to be positioned and aligned may be moved in any direction with ease, and it will be supported in the selected position until finally fixed in place.

In addition to permitting flexibility in element positioning, this type of support structure has a number of other advantages. For instance, the seal between the cup and a vitreous envelope may be made exceptionally strong. The large diameter of such a seal is much more acceptable for supporting the weight of an element than a conventional small diameter wire-glass seal. The joint between the cup-like member and the enlarged portion of the support member forms a heat flow path of large cross-section for efficient conductive cooling of the supported element. Similarly, the large cross-section gives an excellent electrical path to the element. The relatively large diameter and the simplicity of the support provide a low inductance path from the terminal to the element. The simplicity of the structure, furthermore, eliminates capacitive effects which, in the past, have arisen from unduly close spacings between element supports. In general, such a support is strong, strain free, and extremely light.

My support may be used to advantage with any tube element within the vacuum envelope. It is especially valuable for use with a grid structure because positioning of this electrode is particularly difficult. It is advantageous, of course, to minimize the weight which must be carried by such support because heavy tube elements necessitate the use of supports of inconveniently large cross-section and, also, because heavy element complicate the type of joint used between them and their supports.

Accordingly, I have invented a light weight grid structure which is especially valuable for use in conjunction with the above described support structure but which has many advantages when employed in other applications. This grid consists of a plurality of parallel wires arranged in a circle and having convergent portions at one end, secured together at this end, and a ring at the other end, to which ring each wire is affixed. The support may be conveniently affixed to this ring. It will be noted that the ring may be made of light material and that no end structure, other than the wires themselves, is employed at the opposite end of the grid. It

had been felt in the prior art that a reinforced end structure was necessary for the ruggedness of the grid. However, I have determined through experiment that this type of construction is not necessary for ruggedness in many applications.

The grid structure as described, in addition to being simple and light, is rugged and able to withstand even the strain of unusually rough handling. Furthermore, the elimination of spiral windings permits symmetry in electron flow all the way around the grid. Moreover, it eliminates the time consuming task of welding together the cross wires. This welding, in addition to requiring the time of a highly skilled welder, may produce embrittlement of the structure adjacent the welds and hot spots at points where welds are poor. Affixing a spiral at numerous points to the grid wires has, also, caused the introduction of strains into prior art grid structures.

For a better understanding of my invention reference is made to the following drawings:

Fig. 1 shows in cross section an electron tube which employs my invention.

Fig. 2 is a perspective view of the grid and support structure shown in Fig. 1.

In a preferred embodiment, my invention employs a glass, globe-like envelope 10 which has a narrow neck 11 at one end and an enlarged neck 12 at the other end which accommodates a re-entrant envelope portion 12a. The reentrant end portion 12a is terminated in stem press 13 through which passes rod-like conductors 14 and 15. The rod-like conductor 14 extends into the globe-like portion of the envelope 10 and is affixed by welding or other suitable means to the near-press end of spiral filament 16. The opposite end of filament 16 is similarly affixed to rod-like member 17 which lies on the tube's axis and is advantageously terminated within and supported by the stem press 13. The rod-like members 14 and 17 serve the dual function of filament leads within the vacuum envelope and filament support members. A cup-like heat shield 22 is provided to protect the stem press. Outside of the vacuum envelope the conductors 14 and 15 are terminated in flexible filament leads 19 and 20 respectively. An exhaust tubulation 23 is advantageously ported into the vacuum envelope through the stem press 13 so that the tubulation 23 is protected by its location within the reentrant envelope portion 12a.

The grid structure of Fig. 1 is shown in greater detail in Fig. 2. The grid consists of a plurality of parallel wires or strands 24 having convergent portions 24a near one end. These convergent portions are secured together at this end in some convenient fashion, as by binding them with wire 25 and welding them in place. At the opposite end of the grid structure each of the wires is individually affixed to a ring 26. The ring is in turn affixed by welding, brazing, or other convenient means to an elongated relatively rigid support member 27. In this case this support member is tubular and has one end flattened and bent out of the axial line in such a way as to afford a convenient surface for affixing it to the grid ring 26. The end of the support member opposite that attached to the grid structure is terminated in a portion 28 of elipsoidal, spheroidal, or spherical shape. The lip 29a of the cup 29, which is composed of a glass-sealing metal like Kovar, is affixed to a neck 19a in the side wall of the vacuum envelope in a position con-

veniently located for accommodating the support member 27. The ball-like portion 28 snugly fits within cup member 29, preferably in a portion 29b of reduced diameter thereof. Thus, a sort of ball and socket joint is created which, if sufficiently snug, provides a temporary support for the grid element. This joint permits universal adjustment of the position of the supported element. For instance, adjustment of the electrode position along the axis of the support member 27 is accommodated by modifying the depth of penetration of the ball-like portion 28 within the cup 29. All other position adjustment is accomplished by rotation of the ball-like portion 28 within cup 29. Once in the desired position, inadvertent change in position may be prevented by spot-welding the elipsoidal portion 28 to cup 29. Thereafter, a solid, more conductive joint may be made by brazing together the two members.

As shown in Fig. 1, a tubular extension 30 is affixed to ring 26 of the grid structure. A ring 31 of somewhat smaller diameter is affixed to the filament structure (here conductor 14) coaxial with ring 30. These two rings are employed to add capacitance between grid and cathode elements when tube specifications call for more capacitance than the small amount afforded by the opposing surfaces of elements and supports using my greatly simplified type construction. By increasing the amount of surface mutually opposed, the capacitance may be further increased.

At the end of the vacuum envelope opposite the stem press Kovar cup member 33 is sealed to neck 11 of the vacuum envelope. Cup 33 is advantageously made with a reduced diameter portion 33a which snugly accommodates an enlarged portion 34 of elongated anode support 35. The anode 36 is a tubular member preferably with a cap 37 at its supported end. The anode is advantageously supported at three points by wire-like support members 38. These wire-like supports 38 have parallel portions which are advantageously affixed to the anode cap by doubling back on themselves around the edge of the cap. Convergent portions of the wire-like members 38 are terminated in parallel axial portions which advantageously fit and are sealed in an axial hole 35a in the end of member 35. It may be noted that the enlarged portion 34 of the support 35 in this instance is approximately cylindrical. By exercising great care in sealing cup 33 to neck 11 the axial alignment of the cup may be preserved. Then, if member 34 is made perfectly cylindrical and concentric with the support member 35 a snug fit between members 34 and 33 will assure accurate alignment of anode 36 while permitting adjustment of its axial level. If more flexibility in adjustment and positioning of the anode is desired, the enlarged portion 34 may be made elipsoidal or ball-like similar to the corresponding portion 28 of the grid support.

In assembling the tube structure as shown the anode member is advantageously first introduced. Because of accurate alignment of the cup relative to the envelope 10 and the enlarged portion relative to the support, the anode is automatically aligned upon the axis of the tube and needs only to be positioned at the correct axial level and fixed in place. The structure shown in Fig. 2 may then be introduced into the envelope and the grid cage located within the anode structure while the spherical portion 35 of support 34 is positioned within cup 36. If the tube structure

is placed in a glass lathe, or upon some sort of centering fixture, a centering mandrel tool placed within the grid structure will insure its axial alignment and proper positioning relative to the anode. When the proper position for the grid has been found the enlarged portion 35 may be secured to the cup by spot welding without removing the tube from the glass lathe or the fixture. Thereafter, the filament-stem press structure may be placed within the chuck of the glass lathe opposing the envelope and advanced so that the filament is properly introduced within the grid structure. With the filament correctly in place, the vacuum envelope is completed by sealing the portion supporting the filament to the main body of the envelope. The reentrant portion of the envelope 12a as well as stem press 13 support the filament so that the final seal between neck 12 and reentrant portion 12a may be conveniently made at the tube's end. Thus sealed in position, permanent accurate alignment of the filament relative to other electrodes is assured.

I claim:

An electron tube containing an electrode, the support member for said electrode comprising a relatively rigid elongated member one end of which is affixed to said electrode and the other end of which is terminated in an ellipsoidal portion and a metal cup-like member sealed to the vacuum envelope in position to receive the ellipsoidal portion so that the supported electrode may be subjected to universal movement in determining its proper position.
